UNITED STATES PATENT OFFICE.

RAYMOND W. GRIFFITH AND SAMUEL N. HOPE, OF MILWAUKEE, WISCONSIN, ASSIGNEES TO GRIFFITH-HOPE COMPANY, OF MILWAUKEE, WISCONSIN, A CORPORATION OF WISCONSIN.

INSTRUMENT LIGHT.

Original application filed October 6, 1922, Serial No. 592,891. Divided and this application filed August 13, 1924. Serial No. 731,822.

This invention relates to instrument lights for automobiles and the like and has for its object to provide a simple structure that will be compact and neat in its appearance; that will be inexpensive to manufacture; that will be readily adapted to take the usual finish of the instruments on the instrument board, black body with nickel base; that may be quickly and easily assembled for use with either a single wiring system or a double wiring system; that will have its attaching means hidden from view; that will be capable of throwing a light from one side door to the other; that will be provided with a shutter to entirely conceal the lamp or opened to any desired extent to modify the light; that will permit of ready access to the lamp and easy attachment and removal of the lamp, and that will be strong and durable and efficient.

This case constitutes a division of our application for instrument light, Serial Number 592,891, filed October 6, 1922, and issued as Patent 1,557,045, on October 13, 1925.

With the above and other objects in view the invention consists in the instrument light as herein claimed and all equivalents.

Referring to the accompanying drawings in which like characters of reference indicate the same parts in different views,

Fig. 1 is an end elevation of an instrument lamp constructed in accordance with this invention;

Fig. 2 is a front view thereof;

Fig. 3 is a bottom view thereof;

Fig. 4 is a similar view showing the modification for converting it for use with a double wire system;

Fig. 5 is a transverse sectional view;

Fig. 6 is a longitudinal sectional view, and

Fig. 7 is a view of the base with the hood and lamp removed.

Fig. 8 is an enlarged perspective view of a fragment of the socket looking upwardly at the edge thereof shown in Fig. 6.

In these drawings, 10 indicates a base of pressed sheet metal of oval shape, which is deeper at its upper edge, so that its face is approximately vertical when fitting against an inclined instrument board, shown in dotted lines in Fig. 1. The face of the base is embossed or pressed up to form a smaller

oval shaped projection 11, upon which is 55 tightly but removably fitted an oval shaped hood 12 of sheet metal with a rounded front end. A sector-shaped opening 13 is formed in the lower part of the front end of the hood and is controlled by a shutter or shield 60 14 pivotally mounted in the hood and adapted when closed to complete the rounded formation of the hood. The curved shutter or shield 14, which is convex laterally as well as longitudinally, may be pivotally mounted in the hood by projections 65 15 on its ends fitting in openings in the hood, such projections being either in the form of rivet lugs, as shown, or in the form of lugs bent out from the ends of the hood. 70 An outwardly projecting lug 16 at its edge serves as a handle by means of which it may be moved to the desired adjustment and, when it is completely closed, such handle fits within a recess 17 in the edge of the hood 75 opening.

A plate of insulating material 18 fits within the recess in the bottom of the base, where it is held by rivets 19. Insulating washers 20 fit between the heads of the rivets 80 19 and the sheet metal base and the openings in the base are sufficiently larger than the stems of the rivets to avoid contact therewith so that the rivets are insulated from the base. Either or both of these 85 rivets may be used for attaching contact springs 21 to the insulating plate according to whether the instrument light is to be used on a single wire circuit or a double wire circuit. Each contact spring consists 90 of a U-shaped sheet metal spring member attached at an intermediate point to the insulating sheet by the rivet 19, as mentioned, with one end projecting toward the center of the base for engagement with a lamp 95 terminal and the other end bent to form a nut pocket 22 containing an ordinary nut 23, through which is threaded a screw 24 to constitute a binding post. The screw 24 passes through an opening in the nut pocket 100 of the contact spring, threads through the nut and then passes through a close-fitting opening in the insulating plate to anchor the contact spring in place, and then through a considerably larger opening 25 in the base 105 to avoid electrical contact therewith. Openings 26 through the insulating plate and the base permit attaching screws or bolts 27 to

be located within the hood where they will not be seen and their location is such that they do not come in contact with the contact springs, such springs being curved around 5 them and spaced therefrom.

Centered somewhat below the center of the base is an opening 28 through the base and the insulating plate to constitute a socket to receive the base 29 of an electric 10 lamp 30 and notches 31 in the edge of this opening through the base accommodate the diametrically opposite attaching lugs 32 of the lamp base as the lamp base is inserted in or removed from the socket 28, and embossed 15 pockets 33 pressed in the sheet metal base in vertical alignment receive said attaching lugs when the lamp is turned through an arc of movement to its final position. The travel of the attaching lugs 32 from the 20 notches 31 to the pockets 33 is permitted by arc shaped recesses 34 in the edge of the opening of the insulating plate and the lamp is held firmly in place with the attaching lugs 32 fitting in the pockets 33 by the pressure 25 of the contact spring or springs 21 bearing against its terminal or terminals 34.

If desired, the metal which is cut to form the notches 31, may be left bent down from one edge of said notches to form stops 35 to 30 prevent the turning of the lamp in the wrong direction when it is being attached and to limit the turn of the lamp when it is being removed.

In attaching the instrument light, wiring 35 connection is made with the binding post or binding posts 24 and then the base is clamped in place on the instrument board by the attaching screws or bolts 27, the lamp is inserted in the socket and the hood forced 40 in place. Access to the lamp may be had at any time by removing the hood and then the lamp is easily engaged and removed even though the glass bulb has become broken, thus having a great advantage over structures of the tubular socket type.

The lamp being positioned below the center of the hood, serves to throw the light through the partly or fully opened orifice to the full width of the instrument board or 50 from one door of the automobile to the other and, by closing the shutter more or less, the light may be modified to suit the requirements. The shape of the hood and of the shutter enables them to serve as reflectors 55 for strengthening the illumination. If no light is desired at times when the lamp is burning, as when the instrument light is in series with the tail-light, the shutter or shield may be completely closed.

60 It will be seen that the instrument light of this invention is inexpensively constructed of sheet metal stampings and a fiber punching with ordinary rivets, nuts and screws, and is readily assembled without requiring skilled labor and still it is strongly

constructed and amply protected against short circuits or wear that would cause it to get out of order.

It will be further noted that, as the hood is separable from the base, the latter may 70 be readily nickel-plated, while the former is given a dull black finish to harmonize with the instruments on the instrument panel.

The avoidance of the use of a tubular socket to receive the lamp base effects an 75 important economy in construction without sacrificing the strength or efficiency of the device. Furthermore it permits of the structure being more condensed with a corresponding improvement in the appearance. 80

In practice the change from the manufacture of the base for the single wire circuit, shown in Fig. 3, to the base for the double wire circuit, shown in Fig. 4, is effected by merely clipping the ends of the 85 contact springs and the added spring is from the same die as the other, the nut pocket and the bend of the spring being reversed.

What we claim as new and desire to secure 90 by Letters Patent is:

1. In an instrument light lamp socket, a sheet metal base having a flat surface, an insulating plate secured beneath the flat surface of the base, there being an opening through the flat surface of the base and the insulating plate to receive a lamp base, a spring contact mounted on the insulating plate behind said opening to be engaged by a terminal of the lamp base when the lamp 100 base is pressed through the opening, there being notches in the edge of said opening to accommodate the attaching lugs of the lamp base, and pockets formed in the sheet metal base at the edge of the opening to receive 105 the attaching lugs of the lamp base, the insulating plate being cut away along the edge of the opening from the notches to the pockets to accommodate the attaching lugs in their movement between the notches and 110 the pockets.

2. A lamp socket comprising a sheet metal base having an approximately flat surface with an opening therethrough to fit a lamp base, a contact spring behind the opening to be engaged by a lamp terminal when the lamp base is forced through the opening, there being notches in the edge of the opening to accommodate the attaching lugs of the lamp base, pockets at one side of the 115 notches in which the attaching lugs are retained by the pressure of the contact spring, and stops bent up from the sheet metal on the other side of the notches to limit the movement of the attaching lugs. 120

3. In an instrument light lamp socket, a sheet metal base having an approximately flat surface with an opening to receive a lamp base with notches to accommodate the retaining lugs thereof, an approximately flat 125

U-shaped contact spring attached to the back of the flat base at its intermediate portion but insulated therefrom and bent to form a nut pocket at one end and with the 5 other end extending behind the opening to be engaged by a lamp terminal when a lamp base is forced through the opening, a nut supported within the nut pocket, and a screw threaded through the nut to form a binding 10 post.

4. In an instrument light lamp socket, a sheet metal base having an approximately flat surface, an insulating plate secured to the back of the flat surface, there being an 15 opening through the flat surface of the sheet metal base and the insulating plate to receive a lamp base with notches in the edge of the opening to accommodate the attaching lugs of the lamp base, a U-shaped contact spring riveted at its intermediate point to the insulating plate and the base and insulated from the base, one end of said contact 20 spring being bent to form a nut pocket and the other end extending behind the opening 25 to be engaged by a lamp terminal when a lamp base is forced through the opening, a

nut contained in the nut pocket, a screw passing through registering openings in the contact spring, the insulating plate and the sheet metal base and threaded through the 30 nut, said screw fitting the openings in the contact spring and in the insulating plate to anchor the contact spring in place but being loose within the opening of the base to avoid contact therewith. 35

5. A lamp socket for instrument lights comprising a base having an opening to receive the lamp base, an opening on one side thereof to receive an attaching screw, and a U-shaped approximately flat contact 40 spring secured to the back of the base and insulated therefrom and centered around the attaching screw opening but spaced therefrom to avoid contact with the attaching screw and having its end projecting 45 behind the first mentioned opening to engage a lamp terminal when a lamp is passed through said opening.

In testimony whereof we affix our signatures.

RAYMOND W. GRIFFITH.
